DIE

George W. Lamb, Beverly, Mass., assignor to
 United Shoe Machinery Corporation, Paterson,
 N. J., a corporation of New Jersey

Application March 28, 1934, Serial No. 717,735

7 Claims. (Cl. 164—93)

This invention relates to dies and is herein illustrated as embodied in a die for use in ornamenting shoe parts by perforating portions thereof.

- 5 5 One type of perforating die which has come into common use for ornamenting shoe uppers comprises a base carrying a plurality of punches and a depressible work support mounted upon the base for positioning a piece of work above the punches prior to application of pressure to force the punches through the work. It is an 10 object of the present invention to provide a die of the type referred to of improved construction which will permit rapid detachment of the work support when desired, as in instances where the work support must be removed to replace or repair the punches. To this end and as illustrated, the invention provides a die comprising a base having cutting tools supported thereon, 15 a work supporting plate, and yieldable members carried by the base and adapted to engage the plate to support it, together with means on the base and plate for detachably maintaining the plate upon the members in operative relation to 20 the tools.

Other objects and features of the invention will be apparent from the following detailed description when taken in connection with the accompanying drawing and will be pointed out in 25 the claims.

In the drawing,

Fig. 1 illustrates in plan view a die construction in accordance with one embodiment of the invention;

35 Fig. 2 is a side view partly in section of the die shown in Fig. 1; and

Fig. 3 is a detailed view of the means for limiting movement of the stripper plate.

As shown in Figs. 1 and 2, the illustrative die 40 comprises a base plate 10, a punch plate 12 which carries a plurality of punches 14 arranged to produce an ornamental design in a shoe upper, and a work support or stripper plate 16 which is normally operative to support a work piece such 45 as a vamp above the punches preparatory to exerting pressure upon the work in the punching operation, there being openings 18 in the work support through which the punches 14 can operate. The base plate 10 is supported upon 50 rails 20 to which it is secured by set screws 22, this structure facilitating lateral movement of the die into and out of a perforating machine.

The work support 16 is normally supported in a plane slightly above the punches 14 by means 55 of pins or studs 24 each of which extends through

an opening 26 in the punch plate and an opening 28 in the base plate. Each of the pins 24 is provided with a shoulder 30 adapted to engage the under side of the plate 16, there being a spring 32 surrounding the pin and positioned in the opening 26 for forcing the pin upwardly, upward movement of the pin being limited by a set screw 34 which engages the under side of the base plate 10.

10 In order accurately to position the work supporting plate 16 relative to the punches, each of the pins 24 is provided with a reduced portion 36 above the shoulder 30 which is adapted freely to enter an opening 38 in the plate. As shown in Fig. 1, there are four pins 24 which engage the plate, thus accurately to locate it relatively to the punches with the openings 18 in alignment therewith. To provide for support of the plate 16 in large dies, one or more additional pins may be used, such as pin 39 which is similar 15 in construction to pins 24 except that it does not have a reduced portion entering the plate.

20 For detachably securing the work support 16 to the die there are provided members 40 in the form of spring clips having portions 41 riveted to the stripper plate 16 and having leg portions 42 extending at right angles to the plate and each provided with a vertically extending slot 44 adapted to engage a horizontal projection in the 25 form of a pin 46 extending from the base plate 10. The lower portions 48 of the members 40 are bent upwardly to form finger grips for operating the clips. This pin and slot construction operates to permit downward movement of the work support during a punching operation. Normally, however, 30 the plate 16 is urged outwardly of the punches by the springs 32, heightwise movement of the plate being limited by engagement of the pins 46 with the bottoms of the slots 44, thus to secure the 35 plate in engagement with the pins 24 and to maintain the openings 18 therein in alignment with the punches 14.

40 When it is desired to remove the plate 16, as sometimes becomes necessary in replacing a 45 damaged punch, the spring clips 40 are bent outwardly and the plate can then be pulled upwardly off of the studs 24. The plate can readily be replaced merely by pressing the clips over the pins 46 downwardly until the reduced portions 36 of the pins 24 are located within the openings 38 and the pins 46 enter the slots 44 of the clips 40.

50 Having described my invention, what I claim as new and desire to secure by Letters Patent of the United States is:

35

40

50

55

1. A die comprising a base, cutting tools on the base, a work supporting plate, spring-pressed pins mounted upon the base and having portions adapted to engage the under side of the plate normally to support it above the cutting tools, and inter-engaging means upon the plate and base for detachably securing the plate in position upon the pins.
2. A die for ornamenting shoe parts comprising a base, punches mounted upon the base, a work supporting plate, resilient means mounted upon the base for supporting the plate, spring clips carried by the plate and having slots therein, and projections upon the base adapted to enter the slots for limiting heightwise movement of the plate.
3. A die for ornamenting shoe parts comprising a base, punches carried by the base, a work supporting plate, pins slidably mounted in the base and adapted to engage the plate to support it, springs for forcing the plate heightwise of the punches, and a pin and slot connection between the plate and base for limiting heightwise movement of the plate.
4. A die comprising a base, punches carried by the base, a work supporting plate, spring-pressed pins mounted upon the base and adapted to engage the plate normally to support the same above the punches, and means for detachably securing the plate in position upon the pins comprising members depending from the plate and having slots therein, and projections upon the base adapted to enter the slots.
5. A die comprising a base, punches carried by the base, a work supporting plate, members for supporting the plate comprising pins carried by the base and having shoulders for engaging the under side of the plate to support it and reduced portions adapted to enter openings in the plate to locate the plate relatively to the punches, and means for maintaining the plate in position upon the shoulders.
6. A die comprising a base, punches carried by the base, a work supporting plate, a plurality of pins resiliently mounted on the base and having shoulders thereon for engaging the under side of the plate to support it and reduced portions adapted to enter openings in the plate for locating the plate relatively to the punches, and means carried by the plate for detachably engaging the base for securing the plate thereto.
7. A die comprising a base, punches carried by the base, a work supporting plate, a plurality of pins resiliently mounted on the base and having shoulders thereon for engaging the under side of the plate to support it, some of the pins having reduced portions adapted to enter openings in the plate for locating the plate relatively to the punches, and interengaging means carried by the plate and the base for limiting heightwise movement of the plate.
